UNITED STATES PATENT OFFICE.

WALTER P. JENNEY, OF WASHINGTON, DISTRICT OF COLUMBIA.

FIN-GUARD FOR VESSELS.

1,313,946.

Specification of Letters Patent. Patented Aug. 26, 1919.

Application filed November 8, 1913, Serial No. 799,908. Renewed January 9, 1917. Serial No. 141,495.

To all whom it may concern:

Be it known that I, WALTER P. JENNEY, a citizen of the United States, residing at Washington, in the District of Columbia, have invented certain new and useful Improvements in Fin-Guards for Vessels; and I do hereby declare the following to be a full, clear, and exact description of the invention, such as will enable others skilled in the art to which it appertains to make and use the same.

This invention relates to improved fin guards for vessels in general, and has for its objects to provide a means which will protect the propellers, which will lessen the settling or squatting of the stern at high speeds, and one which will also aid in increasing the speed of the vessel.

With these and other objects in view, the invention consists in the novel construction and location of the parts more fully herein-after disclosed and particularly pointed out in the claims.

Referring to the accompanying drawings forming a part of this specification in which like numerals designate like parts in all the views:

Figure 1 is a side elevational view of the stern of a vessel provided with my fin guards;

Fig. 2 is a plan view of the parts shown in Fig. 1;

Fig. 3 is a plan view showing the guards applied to a vessel having more than two propellers;

Fig. 4 is a view in side elevation of the parts shown in Fig. 3;

Fig. 5 is a sectional view on the line 5-5 of Fig. 4; and,

Fig. 6 is a sectional view on the line 6-6 of Fig. 4.

Referring especially to Figs. 1 and 2, 1 indicates a vessel provided with a plurality of propellers 2, carried by the shafts 3, supported by the members 4, and between these propellers and the plane 5 of the normal load water line I locate my fin guards 6 which are rigidly attached to the hull of the vessel.

50 The fin guards 6 as shown are slightly inclined to the plane 5 of the normal load water line in order that they may conform to the direction of the stream lines 7, observed at the maximum or other selected speed for which the vessel was designed.

When thus inclined they offer no material

resistance to the passage of the vessel through the water, while they support the stern and materially lessen the well known settling or squatting so often observed in 60 vessels driven at high speed. This lessening of the settling of the stern serves to maintain the vessel's trim at high speeds and is accompanied by a decrease in resistance to her passage through the water. For this 65 reason my guards permit the vessel to be driven at the same speed with less power, or to be driven at a higher speed with the same power, than would be the case if my said fins or guards were not employed. 70

Further, these guards being normally submerged to a depth providing a clearance for the propellers, tend very materially to lessen the rise and fall of the stern or the pitching of the vessel. They also tend to prevent 75 the stern from rising in ordinary sea ways to a height sufficient for the propellers to come out of the water, and they therefore tend to prevent the engines from racing. 80

In addition to reducing the pitching of the vessel, these guards also tend to reduce the rolling motions, and therefore they serve to materially steady the ship under all conditions. Again, these fins or guards being interposed between the propellers and the surface of the water, shut off access of air from the surface to the propellers, and in this way prevent cavitation. 85

Another important function of these 90 guards is to protect the propellers from injury, as from collisions with docks, with locks of canals, by striking floating timber and in other ways. This said function becomes more important in long and narrow 95 vessels having two or more screws, and in which the overhang of the counters is not sufficient to afford the above protection.

In the form of vessel disclosed in Figs. 4 to 6 wherein four propellers are provided, I 100 place a guard over each propeller. In this case, the forward edges of the forward guards 6 are slightly inclined downward as before in order to conform to the stream lines over the forward propellers 2, and the 105 forward edges of the rear guards 10 are slightly inclined upward to conform to the stream lines over the rear propellers 11. In other words, since the stream lines first incline upward or rise over the forward propellers, and then curve downward as they 110 pass over the rear propellers, as shown, the

guards are reversely inclined to conform to this change in direction.

My said guards should be carefully distinguished from the well known abovewater guards of various descriptions, which are normally not submerged and which cannot perform the functions of my guards. A careful distinction should likewise be drawn between my guards and the well known normally submerged guards, which although of various types, yet generally, involve flat arms or loops of metal extending around or encircling the propellers. These said prior submerged guards are likewise incapable of performing the functions of my guards.

My invention should likewise be carefully distinguished from the well known diving rudders. These are usually adjustable, while my guards are fixed, and in addition, these said rudders are never placed over the screws as are my guards.

In addition to placing my fins or guards at such an inclination to the plane of the normal load water line, as to make them conform to the stream lines for a selected speed, I may sometimes make this angle greater or less than that required by a strict conformity to the direction of the said stream lines. If the angle of the forward guards is made less, the impulse of the water in stream line motion is exerted upon the under sides of the fins and the tendency is to lift the stern; while if the angle be made greater, the impulse of the water is exerted upon the upper sides of the fins, and the tendency is to depress the stern and to increase the resistance. The same principles apply to the rear guards, where the vessel is provided with four screws. In all cases, where the fins are elevated so that the impulse of the water is exerted on their under sides, the resultant forward component of the water striking the fins will tend to propel the vessel ahead. But, of course, this effect will become greater as the forward edges of the fins are lifted.

In some cases, I may place the fins parallel to the plane of the load water line, whereupon the effect will be to lift the stern, and

to diminish the rising of the bow. These fins may be constructed on stream line forms, and may take various shapes, such as warped surfaces, the fins of a fish, the flippers of a whale, etc., also the upper end under surfaces of said fins may be made convex or concave as the case may be, and therefore, I do not wish to be limited to any particular shape or contour. But, they are always made sufficiently strong and rigid to withstand any ordinary strains to which they are likely to be subjected.

This invention differs from that disclosed in my copending application No. 798989, filed Nov. 3, 1913, and entitled war vessels, in that the fins in this application are applicable to vessels in general, while the fins in said copending application coact with a special form of afterbody and therefore constitute an element in a different combination of parts.

What I claim is—

1. A vessel having a plurality of propellers, fins rigidly attached to said vessel, located above said propellers, between said propellers and the load water line, and inclined to the plane of the load water line, substantially as described.

2. A vessel having a plurality of propellers, fins rigidly attached to the hull between said propellers and the plane of the load water line and conforming to the stream lines of the vessel at a selected speed, substantially as described.

3. A vessel having a plurality of propellers on each side thereof, fins attached to the hull over said propellers and between the same and the load water line, and some of said fins being differently inclined to the plane of said load water line, substantially as described.

In testimony whereof I affix my signature, in presence of two witnesses.

WALTER P. JENNEY.
